UNITED STATES PATENT OFFICE.

WALTER F. SUMER, OF MILES CITY, MONTANA.

POCKET COMB, BRUSH, AND MIRROR.

Application filed July 12, 1922. Serial No. 574,450.

To all whom it may concern:

Be it known that I, WALTER F. SUMER, a citizen of the United States, residing at Miles City, in the county of Custer and 5 State of Montana, have invented certain new and useful Improvements in Pocket Combs, Brushes, and Mirrors, of which the following is a specification.

My invention relates to a combination 10 toilet article used for dressing the hair, and the object of the invention is to provide a device of this character which contains a comb and brush, as well as a mirror, made of a size to be conveniently carried in a 15 pocket. The device is constructed in such a manner that when not in use it can be folded so that the comb and brush may be made to retire within the frame, the mirror forming the protecting cover for the 20 brush.

In the accompanying drawing illustrating one embodiment of the invention—

Figure 1 shows a perspective view of the device when folded;

Fig. 2 is a longitudinal section thereof also in folded position, and

Fig. 3 is a side elevation in partial section of the device open and ready for use.

The device consists of a frame 10 having 30 a handle 11 at one end. The frame is provided with a ledge 12 running around its opening at one side thereof.

In the frame the brush 13 fits loosely and around the edge of the brush is provided 35 a flange 14 adapted to engage with the ledge 12 when the device is in open position, as seen in Fig. 3, and the bristles 15 protrude through the opening of the frame. In order to hold the brush in the open position, the 40 comb 16, which is pivoted in the frame on journals 17 in the longitudinal direction thereof, is furnished with a fin 18 which is intended to engage with the flat back 19 of the brush as seen in Fig. 3. The brush 45 has an abutment 20 for the fin which limits the swinging motion of the comb. In alinement with this fin and on the opposite side of the comb the latter is provided with teeth 31 and it will be seen in Fig. 3 that 50 when the bristles 15 of the brush protrude at one side of the frame, the teeth 31 of the comb protrude through the opposite side of the frame and the comb and brush are in this manner locked rigidly together 55 and the device is ready for use.

To put the device into folded position, the teeth 31 of the comb are pushed to one side, so that the fin 18 disengages the abutment 20 of the brush when the latter will fall back from the ledge 12 until the bristles 60 15 are about level with the outer face of the frame 10, while the comb lies flat on the other side thereof, as seen in Figs. 1 and 2.

It will now be understood that the brush 65 13 is only loosely held in the frame and would rattle therein unless held down by some suitable device. Such a device is provided in the shape of a lid or cover 21 of substantially the same contour as the frame 70 10 and is also provided with a handle 22 forming a counterpart of the handle 11 on the frame. On the inner side of the cover 21 is fitted a mirror 23 and when the parts 75 are assembled the mirror 23 lies against the bristles 15 of the brush, as seen in Fig. 2. In order to hold the parts together in this position a tongue 24 is provided near the handle 11 on the frame 10 and a corresponding notch 25 is furnished on the cover 21. 80 With these parts interengaging as seen in Fig. 2, the cover fits very compactly on the frame and the handle, and a snap latch 26 or any other suitable locking means is provided for securing the outer end of the cover 85 21 to the frame 10. An opening 27 is provided in the handle 22 for the purpose of hanging the mirror on a nail in the wall if so desired. Otherwise the mirror may be held in one hand while the brush and 90 comb may be operated by the other hand.

Some of the advantages of my combined brush, comb and mirror may here be enumerated.

On account of its ability to be folded 95 or closed up compactly, this implement takes up very little room and may accordingly be conveniently carried in the pocket or in a hand bag.

With the cover secured in position, there 100 is no danger of breaking either the mirror or any other parts of the implement, nor can the bristles soil or catch in the clothing.

Being small and easy to carry, it will be found of great convenience by travellers, 105 sheep and cattle men, camping and fishing parties, army and navy men and others.

This invention will prevent the spreading 110 of disease through many persons using the same brush and comb provided in hotels,

trains, steamers or other public places, because each individual may conveniently carry his own comb, brush and mirror.

Having thus described the invention, what is claimed as new is:

1. A device of the class described, comprising a frame having a ledge, a brush loosely mounted in the frame and having a flange, and means in said frame adapted to push said brush outwardly until said flange engages with said ledge to firmly hold the brush with its bristles protruding through said frame.
2. A device of the class described, comprising a frame having a ledge, a brush loosely mounted in the frame and having a flange, and means in said frame adapted to push said brush outwardly until said flange engages with said ledge to firmly hold the brush with its bristles protruding through said frame, said means including a member mounted to oscillate in the frame.
3. A device of the class described, comprising a frame having a ledge, a brush loosely mounted in the frame and having a flange, and means in said frame adapted to push said brush outwardly until said flange engages with said ledge to firmly hold the brush with its bristles protruding through said frame, said means including a member mounted to oscillate in the frame, said member having an element adapted to cooperate with the brush for moving the same.
4. A device of the class described, comprising a frame having a ledge, a brush loosely mounted in the frame and having a flange, and means in said frame adapted to push said brush outwardly until said flange engages with said ledge to firmly hold the brush with its bristles protruding through said frame, said means including a member mounted to oscillate in the frame, said member having an element adapted to cooperate with the brush for moving the same, and said member being provided with teeth forming a comb pointing in an opposite direction to said element.
5. A device of the class described, comprising a frame having a ledge, a brush loosely mounted in the frame and having a

flange, means in said frame adapted to push said brush outwardly until said flange engages with said ledge to firmly hold the brush with its bristles protruding through said frame, and a lid having substantially the same contour as the frame, and means for locking the lid to said frame.

6. A device of the class described, comprising a frame having a ledge, a brush loosely mounted in the frame and having a flange, means in said frame adapted to push said brush outwardly until said flange engages with said ledge to firmly hold the brush with its bristles protruding through said frame, and a lid having substantially the same contour as the frame, and means for locking the lid to said frame, said lid having a reflecting surface on one side thereof to contact with the bristles of the brush when the implement is in folded position.

7. A device of the class described, comprising a frame having a retaining member, a brush loosely mounted within said frame and means in said frame adapted to push said brush outwardly against the retaining member, thereby holding the brush with its bristles protruding through said frame.

8. A device of the class described comprising a frame having a retaining member, a brush loosely mounted within one side of said frame and a pivoted comb normally housed within the other side of the frame, said brush being adapted when tilted, to expose its teeth at one side of the frame and the bristles of the brush on the other side thereof.

9. A device of the class described comprising a frame, a brush being mounted within the frame and a comb pivotally mounted within said frame and adapted, when tilted to expose its teeth on one side of the frame and to actuate the brush to expose its bristles on the other side of the frame, said brush and comb being normally housed within the frame.

In testimony whereof I affix my signature.

WALTER F. SUMER. [L.S.]
